ANGULARLY ADJUSTABLE SUPPORT

Fred Hall White, Chicago, Ill., assignor to
Pearl Van Lew White, Chicago, Ill.

Application May 17, 1946, Serial No. 670,495

3 Claims. (Cl. 248—226)

1

The present invention relates to an angularly adjustable support and more particularly to a support which is especially adapted for use where it is desired to support a device or instrumentality in such a manner that it may be adjusted to occupy any relative angular position.

Angularly adjustable supports or adjustable pivotal supports have many applications. In photography, for example, floodlights are extensively used and require adjustable means so that the lights may be brought to bear on a particular subject from any desired angle. Various means have been provided for adjustably supporting such floodlights which have not been entirely satisfactory. Usually such means comprise a clamping screw which is released to obtain movement of the device or instrumentality such as a lamp, for example, relative to its support. In arrangements used heretofore, a minute movement of the lamp or a final critical adjustment thereof was not obtainable since if the clamping screw were loosened sufficiently to obtain movement, the device such as a lamp was likely to move completely out of position. It would be desirable, therefore, to provide an adjustable pivotal support for a device or instrumentality so that it can be moved to any angular position and maintained in such position including means whereby a slight release of the clamping screw will permit even an infinitesimal movement of the device if it is desired without in any way effecting the clamping screw or associated mechanism.

In connection with photographic floodlights, it has been common practice to provide a spring clamp which will grip the edge of any surface whereby the lamp can be fastened to any suitable support such as a chair, table, or the like. Adjustable means are interposed between the spring clamp and the floodlight or the like to adjustably support the light at any angle with respect to the spring clamp. The present invention is also concerned with a simple means of fastening the spring clamp to the new improved adjustable pivotal support of the present invention.

Accordingly, it is an object of the present invention to provide a new and improved support of the above-mentioned type which can be swung with freedom through a wide arc of adjustment and which embodies a novel and simple arrangement for effectively holding the support in a selected position of adjustment.

It is another object of the present invention to provide an adjustable pivotal support for a device in which movement of the device, however small,

2

may be obtained together with accurate positioning thereof regardless of the angle involved.

Still another object of the present invention is to provide an adjustable pivotal support and means for fastening it to a spring clamp of the type commonly used in connection with photographic floodlights.

Further objects and advantages of the present invention will become apparent as the following description proceeds and the features of novelty which characterize this invention will be pointed out with particularity in the claims annexed to and forming a part of this specification.

For a better understanding of the present invention, reference may be had to the accompanying drawing in which:

Fig. 1 is a plan view of a conventional photographic floodlight embodying the adjustable pivotal support of the present invention;

Fig. 2 is an enlarged view of a portion of Fig. 1 taken on line 2—2 thereof;

Fig. 3 is a sectional view taken on line 3—3 of Fig. 2;

Fig. 4 is a view partly in section taken on line 4—4 of Fig. 2; and

Fig. 5 is a sectional view similar to Fig. 3, illustrating a modification of the present invention.

Although the adjustable pivotal support of the present invention is especially useful in connection with photographic floodlighting and the like, it should be understood that it is applicable for a wide variety of purposes as, for example, for holding reading lamps, spotlights, instrument trays, and almost any number of other devices or instrumentalities. It should also be understood that the following description of the invention as applied to a photographic floodlight is by way of example only.

Referring now to the drawings, there is illustrated a photographic floodlight 10 embodying the present invention. This floodlight 10 includes a reflector 11 adapted to be supported from any suitable support by means of a spring clamp 12. The spring clamp 12 is preferably formed of spring wire arranged in the form of a U with a coiled portion 12' comprising a plurality of turns at the base of the U so as to tend to bias the ends of the wire away from each other. However, in order that the ends of the wire may be biased towards each other to produce a clamping action therebetween they are arranged to cross each other as is clearly indicated in Fig. 1 of the drawing, whereby the coiled portion 12' causes deformed clamping portions 12'' to move toward each other so that any suitable member may be

clamped therebetween. Preferably, the clamping portions 12' are covered with resilient material such as rubber or the like as indicated at 13 to prevent damage to furniture or other supporting means to which the floodlight 10 is clamped.

In order to support the reflector 11 and associated lamp not shown from the spring clamp 12 in an adjustable manner so that light may be thrown in any desired direction, there is provided the pivotal support of the present invention generally indicated at 14 which comprises a U-shaped member 15 having the base or bight of the U fastened to the spring clamp 12 as will be described hereinafter. The ends of the U-shaped member 15 are connected to the adjustable pivotal support of the present invention comprising a rotatable cylindrical member 16 having a pair of cone-shaped recesses 17 and 18, respectively formed therein, one positioned at either end of the rotatable cylinder 16. Arranged in interfitting relationship with respect to the cylinder 16 are a pair of cone-shaped members or washers 19 and 20. The cone-shaped members 19 and 20 are shaped so as to have the same angle as the recesses 17 and 18, whereby the end pieces 19 and 20 touch the cylindrical member 16 throughout the entire interfitting conical surfaces thereof which are in frictional engagement. Although the cylindrical member 16 is rotatable, the end pieces 19 and 20 are stationary being held in this manner by the ends of the U-shaped member 15 which fit into recesses 21 and 22 formed in end pieces 19 and 20, respectively, as is clearly shown in Figs. 2 and 3 of the drawings. It should be understood that any other suitable means for holding end pieces 19 and 20 in fixed relationship with U-shaped member 15 may be equally well employed.

To hold the U-shaped member 15, the rotatable cylindrical member 16 and the end pieces 19 and 20 in the assembled relationship shown in the drawing, one arm of the U-shaped member 15, the end piece 20, the cylindrical member 16, and the end piece 19 are provided with aligned apertures 23, 24, 25 and 26, respectively. Also, the other arm of the U-shaped member 15 is provided with a tapped opening 27 so that a clamping screw or bolt 28 which is extended through apertures 23, 24, 25 and 26 may threadedly engage the tapped opening 27 so as to not only hold the members in assembled relationship but also to apply a clamping force to the interfitting conical surfaces. As illustrated, the clamping screw 28 is provided with a winged head 29 so that it may readily be manually adjusted with respect to the clamping force applied to the interfitting conical surfaces.

In order to fasten the U-shaped member 15 to the spring clamp 12 there is provided, as is best shown in Figs. 2 and 4 of the drawing, a suitable clamping bolt 30 having an aperture 31 therethrough into which the spring wire of the clamp 12 may extend. This clamping bolt 30 may be positioned on spring clamp 12 by removing the protecting portion such as the rubber tube 13 from one end thereof and sliding the bolt into position so that the center turn of the coils 12', as is clearly shown in Fig. 2 of the drawing, passes through the opening 31. A suitable lock washer 32 and a nut 33 may then be applied to the bolt 30 which extends through an opening 34 in the base or bight of the U-shaped clamp 15 firmly to fasten the spring clamp 12 to the U-shaped member 15. It will be understood that other means may be employed for fastening the spring

clamp 12 to U-shaped member 15. For example, one or more of the turns may be welded to the U-shaped clamp 15. In certain situations this may not be desirable, however, in view of the fact that such welding might interfere with the operation of the clamp 12. The particular arrangement described and disclosed in the drawing is very simple and inexpensive and in addition, it satisfactorily fastens the U-shaped member 15 to the clamp 12 without interfering with the operation of either member.

Any suitable means may be provided to fasten the rotatable cylinder 16 to the reflector 11 which, of course, supports the lamp socket and flood lamp not shown in the drawing. One such means illustrated in the drawings comprises a ball 36 which is threaded by any suitable means into a threaded aperture in cylinder 16 as is clearly shown at 37 in Fig. 2 of the drawing. The reflector 11 is provided with a cylindrical extension 11' within which is supported the lamp socket, not shown. This cylindrical extension 11' provides a very satisfactory means for clamping the reflector 11 to the ball 36 described above. One means of accomplishing this is illustrated in Figs. 1 and 2 of the drawing and comprises a pair of identical members 38 which are provided at one end with a curved portion for fitting around the cylindrical extension 11' of the reflector 11 and at the other end with a semi-spherical depression so as to fit around ball 36. A bolt 39 having a winged head 40 and a wing nut 41 is provided to clamp the members 38 so as firmly to hold the reflector 11 to the ball 36. An opening 42 is provided in the end of the cylindrical extension 11' so that an electrical connection with the lamp socket within the reflector 11 may be made through this opening. The electrical circuit or cord for supplying the fixture within reflector 11 with electrical energy is not shown in the drawing.

With the arrangement described thus far, the wing nut 41 is released slightly to make rough adjustments by moving the reflector 11 with reference to the ball 36. However, the final adjustments are made with the adjustable pivotal support 14. The screw 28 is loosened sufficiently to permit rotational movement of cylinder 16. The cone-shaped end pieces 19 and 20 cooperating with the cone-shaped recesses in cylinder 16 provide a very smooth control and in effect produce a "velvety" clutch arrangement. Preferably the members 16, 19 and 20 are formed of a suitable metal having polished interengaging surfaces. Steel, brass and other metals have been found suitable. In certain cases it has also been found desirable to employ interfitting parts made from molded insulating material such as a suitable plastic of some sort. With this arrangement, adjustment of the pivotal support may be made affording either large movement of the cylinder 16 or an infinitesimal movement thereof. Whenever cylinder 16 is positioned, it will remain in that position since the adjustment of screw 28 will provide any desired friction which furthermore insures smooth movement of the cylinder 16 as contrasted with the jerky movement of prior arrangements. Consequently, the difficulties encountered in prior art arrangements where a slight movement of the support to obtain the desired positioning resulted in loosening the support with the consequent requirement of complete resetting thereof, is completely eliminated.

In the event that still more accurate control is desired, the number of interengaging conical

surfaces which move relative to each other may be increased as is illustrated in Fig. 5 of the drawing for example. The corresponding parts of Fig. 5 are designated by the same reference numerals as in Fig. 3. In this case, the end pieces 19 and 20 and the U-shaped member 16 and the screw 28 are substantially identical. However, the rotatable cylindrical member 16 is replaced by a cylindrical member 44 having outwardly extending conical surfaces 45 at either end thereof. Between the member 44 and the end piece 19 there is provided a cylindrical member 46 having a conical recess 47 at either end thereof. Similarly, a cylindrical member 48 is interposed between cylindrical member 44 and the end piece 20. The cylindrical member 48 is provided at either end with a conical recess 49. The assembly of the parts is obvious from the disclosure of Fig. 5 and it will be observed that the arrangement functions in the same manner as the adjustable pivotal support 14 described above except that additional interengaging conical surfaces are provided.

In view of the detailed description included above, the operation of the adjustable pivotal support of the present invention will be obvious to those skilled in the art and no further description is included herewith.

It should be understood that the present invention is not limited to the specific details of construction herein illustrated and that changes and modifications may occur to one skilled in the art without departing from the present invention, and it is therefore aimed in the appended claims to cover all such changes and modifications as fall within the true spirit and scope of the present invention.

I claim:

1. In a pivotal support for a lamp which is adjustable to any position within predetermined angular limits, a rotatable member supporting said lamp and having a cone-shaped recess in either end thereof, a pair of stationary cone-shaped washers adapted to fit into said recesses, aligned apertures in said member and said washers, means for holding said member and said washers in interfitting relationship and for locking said member in adjustable position comprising a U-shaped member and a bolt, said bolt extending through said apertures and engaging

the arms of said U-shaped member, and means for holding said washers in fixed relationship relative to said U-shaped member comprising a recess in each of said washers for receiving the arms of said U-shaped member.

2. In a pivotal support for holding in a stationary position a device such as a lamp, a rotatable member supporting said device and having cone-shaped end surfaces, a pair of washers having cone-shaped portions adapted to engage said end surfaces, aligned apertures in said rotatable member and said washers, means for holding said member and said washers in interfitting relationship and for locking said member in adjustable position comprising a U-shaped member and a bolt, said bolt extending through said apertures and engaging the arms of said U-shaped member, and means for holding said washers in fixed relationship relative to said U-shaped member.
3. An adjustable pivotal support for a normally stationary device or instrumentality comprising a rotatable member supporting said device and having conical end surfaces, a plurality of members associated with each end of said member having interengaging conical surfaces, one each of which engages with the associated one of said conical end surfaces, aligned apertures in said rotatable member and said plurality of members, means for holding said rotatable member and said plurality of members in interengaging relationship and for locking said rotatable member in adjustable position comprising a U-shaped member and a bolt, said bolt extending through said apertures and engaging the arms of said U-shaped member, and means for holding only some of said plurality of members in a fixed position relative to said U-shaped member.
